UNITED STATES PATENT OFFICE.

CLAIBORN BURTON COOK, OF FOREMAN, ARKANSAS, ASSIGNOR OF ONE-HALF TO
GEORGE L. FELTON, OF ARKINDA, ARKANSAS.

AUTOMATIC SWITCH FOR TELEGRAPH-RECEIVING SYSTEMS.

1,246,551.

Specification of Letters Patent. Patented Nov. 13, 1917.

Application filed July 12, 1916. Serial No. 108,808.

To all whom it may concern:

Be it known that I, CLAIBORN B. COOK, a citizen of the United States, and a resident of Foreman, in the county of Little River 5 and State of Arkansas, have invented a certain new and useful Improvement in Automatic Switches for Telegraph-Receiving Systems; and it consists in the combinations, constructions, and arrangements hereinafter described and claimed.

An object of my invention is to provide an automatic switch for connecting the lines successively with a sounder.

A further object of my invention is to 15 provide a simple device for switching one circuit and then another to the sounder.

Other objects and advantages will appear in the following specification and the novel features of the invention will be particularly 20 pointed out in the appended claims.

My invention is illustrated in the accompanying drawings forming a part of this application, and in which:

Figure 1 is a diagrammatic view of the 25 circuit connection;

Fig. 2 is a section on the line 2—2 of Fig. 7;

Fig. 3 is a perspective view of a portion of the switch;

Fig. 4 is a detail view of the brushes;

Fig. 5 is a perspective view of a jack used in connection with the device;

Fig. 6 is a perspective view of the switch; and

Fig. 7 is a sectional view through the switch.

In telegraph offices where one operator works more than one wire, it is customary to use a resonator containing the telegraph 40 sounders and to connect the various lines periodically with the resonator in order that the operator may be sure of getting his call from any of the lines. The switching of any particular line on to the resonator or sounder circuit is accomplished by means of a jack or plug. Since the sound of the resonator will drown the sound of the instrument on any other line, the operator must go to the switch at intervals and switch the circuit on from the other lines to the resonator in order to ascertain if he has been called, or if he is being called. Where the operator has to attend to other duties, it will be readily seen that this is a matter that requires 45 considerable time.

The purpose of my invention is to provide a device which will automatically connect a sounder first with one line and then with another in succession, so that the operator does not have to make this connection himself. 60

Referring now particularly to Fig. 7, I have shown therein a clock train A. It will be understood, however, that any motor might be substituted for the clock train without departing from the spirit of the invention. This clock train includes a gear B, which is mounted on a shaft C having an insulating sleeve D surrounded by a conducting sleeve E. The latter has cutaway portions such as those shown at e¹, e², and e³, these cutaway portions being arranged about 65 120° apart.

A second shaft is provided with an insulating sleeve G to which are pivotally mounted brushes g¹, g², and g³, respectively. These brushes are held by a spring H in contact with the sleeve D or the sleeve E, and the spring has an adjusting device K. 70

As will be seen in Fig. 7, the casing L 80 is provided with three binding posts 1, 2 and 3, respectively, which are connected by means of conductors 1', 2', and 3', respectively, with corresponding binding posts 1^x, 2^x, and 3^x (see Fig. 2). Wires 1^y, 2^y, and 3^y 85 connect the brushes g¹, g², and g³, respectively. The sleeve E on the shaft C is electrically grounded with the frame of the clockwork. A conductor 5 connects the binding posts with the frame of the clockwork. A switch arm 7 connects the binding post 6 with any of the three binding posts 1^x, 2^x, and 3^x, by moving the switch to the corresponding binding post. The clockwork frame is also connected by means 90 of a conductor 8 with a jack 9 whose spring 10 is connected by a conductor 11 with the battery B. This battery B is a local battery and the sounder S is in circuit with the battery. The wires 12, 13 and 14 lead from the 95 relays I, II, and III, and connect with the binding posts 1, 2 and 3, respectively. 100

From the foregoing description of the device, the operation will be readily understood. The spring is wound, or if a motor 105 is used, it is set going, and the shaft C revolves, thus bringing the brushes g¹, g², and g³, into contact with the conducting sleeve E, successively. Only one brush is in contact with this conducting portion at one 110

time, the other two being on insulated portions, so that the local circuit is connected with the relays I, II, III in succession, and for a predetermined period. Assuming that 5 the switch makes a complete round of the wires, say every 21 seconds, the switch will be on number 1 wire seven seconds, on number 2 seven seconds, and on number 3, seven seconds, being off each wire fourteen seconds. It will be readily seen that one would have to call the operator less than fourteen seconds at most without coming onto the resonator circuit. This arrangement leaves the operator free to attend to other duties 10 in the knowledge that when his call comes, he will hear it.

In the event that it is desirable to keep one of the relays in permanent connection with the local circuit containing the sounder, 20 I may move the handle 7 to the corresponding binding post 1^x, 2^x, or 3^x, thus grounding the relay on the frame of the motor.

The jack shown at 9 and 10 is for the purpose of connecting any other line in the 25 ordinary manner by plugging in at the opening 90 in the casing L, this opening being shown in Fig. 5.

I claim:

1. An automatic switch comprising a 30 frame, a motor carried thereby, a revolving shaft having insulating and conducting portions, said shaft being driven by said

motor, an auxiliary shaft, an insulating sleeve carried by said auxiliary shaft, a plurality of brushes carried by said insulating sleeve and arranged to engage said first-named shaft, each brush engaging first the conducting portion and then the insulating portion of the shaft during the rotation of the latter, and means for maintaining the 40 brushes in engagement with the revolving shaft.

2. An automatic switch comprising a frame, a motor carried thereby, a revolving shaft having insulating and conducting 45 portions, said shaft being driven by said motor, an auxiliary shaft, an insulating sleeve carried by said auxiliary shaft, a plurality of brushes carried by said insulating sleeve and arranged to engage said first-named shaft, each brush engaging first the conducting portion and then the insulating portion of the shaft during the rotation of the latter, and means for maintaining the 50 brushes in engagement with the revolving shaft, said last-named means comprising an arm carried by said insulating sleeve and a spring secured to said arm at one end and to a rigid support at the other end.

CLAI BORN BURTON COOK.
